(57) **CLAIM**

The ornamental design for a window shade switch for aircraft, as shown and described.

DESCRIPTION

FIG. 1 is a front perspective view of a window shade switch for aircraft;

FIG. 2 is an enlarged front perspective view of the window shade switch;

FIG. 3 is a front view of the window shade switch;

FIG. 4 is a bottom view of the window shade switch, to which a top view is identical and not illustrated; and,

FIG. 5 is a first side view of the window shade switch, to which a second side view is identical and not illustrated.

The broken lines illustrate structures that form no part of the claimed design.
